UNITED STATES PATENT OFFICE.

ALONZO G. KINYON, OF CHICAGO, ILLINOIS, ASSIGNOR TO POWDERED COAL ENGINEERING & EQUIPMENT COMPANY, OF CHICAGO, ILLINOIS, A CORPORATION OF DELAWARE.

DEVICE FOR AERATING POWDERED FUEL.

1,307,365.

Specification of Letters Patent. Patented June 24, 1919.

Application filed December 4, 1917. Serial No. 205,395.

To all whom it may concern:

Be it known that I, ALONZO G. KINYON, a citizen of the United States, residing at Chicago, in the county of Cook and State of Illinois, have invented certain new and useful Improvements in Devices for Aerating Powdered Fuel, of which the following is a specification.

In devices of the character to which my invention relates it is the aim and purpose to separate as far as possible each of the finely divided particles of fuel from the others, surround it completely with air sufficient in quantity for its combustion and support it in the air until it emerges from the burner where the mixture of fuel and air is raised to a temperature at which combustion takes place. The purpose of my invention is to provide means by which this aeration of the fuel and the supply of particles with air necessary for its perfect combustion is more effectively accomplished than in the devices of the prior art.

In the accompanying drawings I have shown and in the following specification described in detail the preferred form of my invention. It is to be understood, however, that the specific disclosure is for the purpose of exemplification only, the scope of the invention being defined in the following claims, in which I have endeavored to distinguish it from the prior art so far as known to me without, however, relinquishing or abandoning any portion or feature thereof.

Referring to the drawings Figure 1 is a side elevation of a device embodying my invention with a portion of the wall of a furnace to which it is applied shown in section; Fig. 2 is a vertical section on an enlarged scale of said device; Fig. 3 a transverse section on an enlarged scale on the line 3—3 of Fig. 2; Fig. 4 a longitudinal vertical section on the line 4—4 of Fig. 3; Fig. 5 an elevation of a detail; Fig. 6 a transverse vertical section enlarged on the line 6—6 of Fig. 2; Fig. 7 an enlarged transverse section on the line 7—7 of Fig. 2; and Fig. 8 a detail elevation of the same part.

Referring to Fig. 1 the furnace wall 9 is formed with a burner opening 10 to which a conduit 11 leads from my improved aerating device. The aerating device proper is shown at 12 and receives finely powdered

fuel from a hopper 13 and a supply of air 55 from the fan 14. The hopper and fan may be of any usual or approved design. The aerator or mixing device comprises a mixing chamber 15 which at one end 16 is in direct communication with the burner opening, 60 and at the other end communicates by a tubular conduit 17 with the hopper 13, said conduit extending under said hopper and opening into the bottom thereof at 18. The coal or other powdered fuel is fed through 65 the conduit 17 by a screw conveyer 19 which also forms a means for supplying a certain proportion of the air to be mixed with the fuel, being made hollow for this purpose. Conveyer 19 extends beyond conduit 17 in 70 which it is packed at 20 and the conveyer is rotated by means of a beveled pinion 21 thereon driven from a jack shaft 22 which may be rotated by any suitable motor and transmits motion to the fan by belt pulleys 75 23, 24 and belt 25.

As heretofore stated the tubular screw conveyer 19 is provided with a worm only for that portion thereof within the conduit 17, but is extended beyond the conduit into 80 the mixing chamber where it is perforated and provided with burs, teeth or projections which serve to agitate the mixture of air and fuel in the mixing chamber and more thoroughly intermingle the same. The perforations 26 immediately adjacent the end of the screw portion of the tubular conveyer are substantially perpendicular to the axis of the tube, but the perforations beyond are inclined with reference to said axis in a direction to project the air in series of jets inclined outwardly with respect to said conveyer and forwardly toward the burner. The construction will be best understood by reference to Figs. 3, 4 and 5 in which the inclined openings 27 are shown arranged in circular series and each provided with a bur or blade 28 correspondingly inclined. The end 29 of the conveyer may be perforated as at 30 for the purpose of propelling jets of 90 air to direct the mixture toward the burner. A further supply of air is provided by surrounding the mixing chamber with an annular air chamber 31 which receives its supply from the fan by the by-pass 32. Communication between the annular air chamber and the mixing chamber is provided by striking up from the metal wall of the mix-

ing chamber inwardly projecting tongues 33 leaving openings 34 in said wall.

In operation the coal is fed forwardly in the conduit 17 by the screw conveyer 19 until it reaches the mixing chamber where it is impinged upon by the radial jets issuing through the openings 26 in the tubular conduit, the air being supplied by the fan as previously described. The air mixes with 10 the powdered fuel which is then carried on toward the burner and past the inclined jet openings in the conveyer, constantly receiving additional supplies of air. The inclined forwardly directed openings cause a 15 constant suction and movement of the mixture of fuel and air toward the burner. Not only is the fuel supplied with additional air through the openings 27 in the conveyer, but also receives supplies of air from the annular chamber through the openings 34, the 20 blades or tongues 33 of which also have the effect of directing the entering air forwardly toward the burner as well as inwardly. The blades or tongues 33 and the 25 teeth or burs 28 having relative rotary motion serve to cut and break up the streams of mixed air and fuel moving toward the burner, effectually preventing any massing together of the particles of coal and insuring 30 the segregation of the individual particles and the surrounding thereof with an envelop of air of combustion.

I claim:

1. In a device of the class described, an 35 elongated mixing chamber, a conduit connected to one end thereof, a hopper opening into said conduit, a tubular conveyer in said conduit and mixing chamber, said conveyer having a worm in said conduit and perforated 40 rated in the mixing chamber, teeth on said conveyer in the mixing chamber, means for

rotating the conveyer, and an exhaust conduit leading from the end of the device opposite that to which the hopper is connected.

2. In a device of the class described, an 45 elongated mixing chamber, a conduit connected to one end thereof, a hopper opening into the conduit, a tubular conveyer in said conduit and mixing chamber, said conveyer having a worm in the conduit and being perforated in the mixing chamber, teeth overlapping the respective perforations in the conveyer, said teeth being directed outwardly toward the exhaust end of the mixing chamber.

3. In a device as described in claim 1, the combination with the mixing chamber of an air chamber surrounding the same, the wall between the air chamber and mixing chamber being perforated, and means for supplying the air chamber with air under pressure.

4. In a device of the class described, a mixing chamber having an outlet at one end thereof, a conduit connected to the other end thereof, a hopper communicating with the conduit, a hollow conveyer in the conduit extending into the mixing chamber, a screw on the conveyer, means for rotating the conveyer, said conveyer being perforated with 65 in the mixing chamber, the perforations being inclined toward the outlet of said chamber, teeth overlying the respective perforations and directly outwardly and toward the exhaust end of the chamber, the wall of the 70 mixing chamber being perforated, an air chamber surrounding the perforated portion of the wall of the mixing chamber, and means for supplying the air chamber with air under pressure.

ALONZO G. KINYON.
